W. M. A. SMITH

FOUNTAIN BRUSH

Filed Dec. 11, 1922

UNITED STATES PATENT OFFICE.

WILLIAM M. A. SMITH, OF DALLAS, TEXAS, ASSIGNOR OF ONE-HALF TO (MRS.) ROSE BARNETT, OF DALLAS, TEXAS.

FOUNTAIN BRUSH.

Application filed December 11, 1922. Serial No. 606,244.

To all whom it may concern:

Be it known that I, WILLIAM M. A. SMITH, a citizen of the United States, residing at Dallas, in the county of Dallas and State of Texas, have invented certain new and useful Improvements in Fountain Brushes, of which the following is a specification.

This invention relates to tooth brushes and the primary object thereof is to provide a brush which is of simplified and improved construction, involving a minimum of parts compactly assembled and efficient in operation.

A further object of the invention is to provide a device of this type with improved means for connecting the bristle-carrying member and the cover thereof to the handle.

Further and other objects will later appear.

20 In the drawings:—

Figure 1, is a side elevation with the cover applied;

Figure 2, is a central longitudinal sectional view;

25 Figure 3, is a bottom plan view, parts being broken away and in section;

Figure 4 is a side elevation, partly broken away and in section showing a paste tube connected to the container;

30 Figures 5, 6 and 7 are sections on lines 5—5; 6—6; and 7—7 respectively of Figure 1, and

Figure 8 is a section on lines 8—8 of Figure 3.

35 A cylindrical handle 1 is employed which has an exteriorly threaded neck 6 formed with a conical threaded opening 7. A follower 5 is frictionally engaged within the cylinder 1 so as to be held against rotation, and is slideable by means of a threaded rod 4, the threads of which engage the follower.

40 Rod 4 has a finger engaging head 3 to rotate same and also has a collar 3^a engaging the outer end of the cylinder to prevent longi-

tudinal movement of the rod. The bristles 45 10 are set in a head 8^a which latter is enlarged at its inner end and provided with a curved chamber 8 the outer end of which latter is of circular form and interiorly threaded to engage with the exterior threads 50 of the neck 6. Ducts 9 are formed in the head and extend from the chamber 8 through the central part of the upper side face of the head, as depicted in Figures 2 and 3. A cover 11 is provided for the 55 bristles, the latter having an inner circular neck formed to engage with the circular part of the head 8^a and to lie flush with the periphery of the cylinder 1 and abutting the inner end of the latter.

By removal of the head 8^a and the cover 11 from the neck 6, a tube 12 of paste, may be secured to the neck 6, by threading of its neck 12^a into the threads 7 of the cylinder neck 6 the threads being of conical form so 65 as to accommodate paste tubes having threaded necks of different sizes. Opening α in the cylinder permits air to enter the cylinder in back of the follower.

The neck 6, the head 8^a and the cover 11 70 are formed so that the head and cover will engage the inner end of the cylinder 1 and the cover will lie flush with the periphery of the cylinder 1.

What is claimed is:—

75 In combination with a container having an internally and externally threaded neck, a brush head having a threaded portion for engagement with the external threads of the container neck, the internal portion of the 80 neck being of conical formation whereby paste tubes having different sized threaded necks may be detachably engaged therewith for filling the container.

In testimony whereof I have signed my 85 name to this specification.

WILLIAM M. A. SMITH
